UNITED STATES PATENT OFFICE.

FRANK BYCROFT KEALL, OF LEICESTER, ENGLAND, ASSIGNOR TO UNITED SHOE MACHINERY CORPORATION, OF PATERSON, NEW JERSEY, A CORPORATION OF NEW JERSEY.

PERFORATING.

Application filed December 31, 1924, Serial No. 759,020, and in Great Britain January 29, 1924.

This invention relates to punching machines. The invention is exemplified with special reference to the forming of ornamental perforations in boot or shoe parts, such, for example, as toe tips or vamps.

In perforating the tips of shoe uppers, and particularly tips which are pointed or peaked, it is essential to satisfactory ornamentation that the recurrent units comprising the ornamental design be arranged symmetrically with respect to the point or peak of the tip and usually it is desired that the perforations or groups of perforations be equally spaced. Equal spacing and symmetry of the angularly related rows of perforations at either side of the peak of the tip may be obtained by the use of punching machines employing dies by which all the desired perforations are made at one operation of the machine and in precisely the correct relation to each other and to the peak of the tip. The use of such machines, however, involves a good deal of expense in die equipment, particularly in view of the

great variety of styles and sizes commonly manufactured and in view of rapidly changing styles. Quite commonly, therefore, it is preferred to make the perforations by the use of step-by-step perforating machines, thus avoiding the heavy die equipment expense referred to.

The use of step-by-step perforating machines has, however, been open to the serious disadvantage that heretofore there has been no practicable way of obtaining the desired symmetrical arrangement of the perforations. It is not practicable to start perforating at the end of a tip on one side and to perforate continuously round the tip to the end at the other side, because then there is no assurance that there will be a symmetrical arrangement of the perforations nearest to the point or peak of the tip on either side of it. Moreover, this difficulty is aggravated by the fact that it is usually desired to have one perforation or group of perforations exactly at the peak of the tip, and there is no practicable way of insuring this result if step-by-step perforating be done as just suggested. On the other hand, as step-by-step perforating machines have heretofore been constructed, the edge gage was constructed and arranged for en-

gagement with the work at one side of the line of feed only, and similarly the presser foot was adapted to engage the work at one side of the line of feed only.

Consequently, it has been the common practice for the operator to start perforating at the peak of the tip, and, having finished a row of perforations along one side of the tip, to reverse the work and begin again on the other side of the tip at its end and perforate toward the peak, allowing the machine to operate continuously until the row of perforations was nearly completed and then causing the machine to make single operations while controlling the spacing of the perforations manually, the remainder of the line of perforations being subdivided by guess in an effort to space the perforations as evenly as possible. Thus, step-by-step perforating resulted in irregular spacing and the perforating was slowed down considerably by the practical necessity of proceeding as above outlined in finishing the second row.

In view of the foregoing, it is an object of this invention to provide for producing angularly related intersecting rows of perforations so as to insure even spacing and symmetrical arrangement of the perforations with relation to a reference point such as the peak of a shoe tip, while retaining the advantages characteristic of step-by-step perforating.

To this end, in one aspect, the invention provides a novel step-by-step perforating machine organization having work-positioning means and work-holding means each constructed and arranged to engage the work alternatively on either side of the line of feed. In this aspect, features of the invention consist in the provision in a step-by-step perforating machine of reversible work-positioning and holding means, illustrated as comprising a reversible presser-foot and a double-edged gage readily shiftable to permit perforating on either side of the line of feed. Other features of the invention consist in a construction and arrangement which provides for quickly and accurately adjusting the reversible presser-foot, as by tilting it to bring one or the other of its work-engaging surfaces into engagement with the work, and in means for conveniently shifting the

double-edged work-gage into its alternative positions.

In another aspect, the invention resides in an improved method of step-by-step perforating to produce angularly related intersecting rows of perforations, which consists in making an initial perforation in a predetermined relation to a reference point, such as a point which will be at the corner between the rows, forming one row of perforations while moving the work to perforate progressively away from the reference point, and then commencing again in predetermined relation to the reference point and forming a second row of perforations, moving the work to perforate progressively along the other side of the angle. In the case of a pointed tip, the work is guided preferably first with reference to the edge adjacent to the first row of perforations and then is returned to the starting corner and is guided with reference to the edge of the work adjacent to the last-mentioned row of perforations and on the opposite side of the line of feed from the position of the reference edge first employed.

Thus, the present invention insures a symmetrical arrangement of perforations in pieces of work having characteristics such as the characteristics of peaked shoe tips above referred to, since the initial perforations or groups of perforations on each side of a reference point, such as the peak of a pointed shoe tip, have the same predetermined relation to that reference point, and at the same time the perforations may be evenly spaced.

Still other features of the invention will become apparent upon consideration of the following description and claims taken in connection with the accompanying drawings in which:

Fig. 1 is a front elevation of a perforating machine embodying my novel work-positioning and holding means;

Fig. 2 is a plan view partly in section of the work-supporting table showing my novel presser foot and edge gage;

Fig. 3 is a perspective view of a portion of this mechanism;

Fig. 4 is a front elevation of the work-supporting table illustrating my novel work-positioning means together with the mechanism for adjusting the edge gage;

Fig. 5 is a perspective view of the edge gage viewed from its under side;

Fig. 6 is a fragmentary transverse section through the edge gage;

Fig. 7 is a perspective view of the under side of the adjusting lever for moving the edge gage from one position to another;

Fig. 8 is a side elevation of the presser foot mechanism;

Figs. 9 and 10 illustrate successive steps in the method of operation.

In perforating work having angularly related rows of perforations meeting at a common point or a corner, such as that found in a pointed tip or in a vamp correspondingly formed, as has been explained, it is essential to satisfactory ornamentation that one of the perforations shall be located exactly at or substantially at a predetermined distance from the center of the peak of the tip or vamp. A pointed tip of this type has been illustrated in the drawings in Figs. 9 and 10, and in perforating work of this character, it has heretofore been the practice for the operator to commence perforating at the peak of the tip, as indicated by the letter A, or at a predetermined distance therefrom and to perforate it along one side, as along the portion A—B of the edge of the tip. As illustrated the reference point A is at the peak of the tip as it is usually desired to have a perforation at this point. Step-by-step perforating machines, such as have been employed for this operation, commonly feed the work away from the operator and are provided with an edge gage which contacts with the right-hand edge of the work as it is moved along. Therefore, when the operator has completed the first row of perforations, it has been the custom to perforate the other side of the tip from a point indicated by the letter C toward the peak of the tip. In making the second row of perforations, it has been the custom to perforate along the portion indicated by C—A until the work has been perforated to within a short distance of the point A, and then to divide the remaining distance by guess, and make the remaining perforations by single operations of the machines.

The illustrated machine, by the use of which my novel method may advantageously be performed and which embodies various features of the invention, is a step-by-step perforating machine of the type illustrated in U. S. Letters Patent No. 941,704, granted Nov. 30, 1909, on the application of L. W. G. Flynt, to which patent reference may be had for a full disclosure of parts not fully disclosed herein. This machine comprises a frame 12 carrying a work-supporting table 14, said frame having an overhanging arm 16 in which there is journaled a main shaft 18 for the operation of a punch bar 20 which is both reciprocated vertically and swung laterally, to the rear when the machine is viewed as in Fig. 1, to feed the work. An adjusting screw 22 in connection with other mechanism permits the adjustment of the length of feeding step while a lever 24 held in adjusted position by means of a thumb nut 26 allows an adjustment of the depth of the punch stroke. In order to hold the work during the intervals between the feeding movements, a presser foot mechanism is employed comprising a presser foot bar 32

which is urged downwardly by means of a spring 34 and lifted intermittently in timed relation to the feeding movements by means of a lever 36. The punch unit 37, as herein illustrated, is made up of three tubes, a larger tube 38 (Fig. 3) and two smaller tubes 39. It will be understood, however, that any other form of punch may be substituted to suit the wishes of the user.

10 The presser foot mechanism is supported from the lower end of the presser foot bar by means of a rearwardly and laterally extending bracket 40 by means of which there is supported for sliding and pivotal adjustment a reversible presser foot 42 having work-contacting toes 44 (Fig. 8) at the ends of a horseshoe-shaped portion 50 (Fig. 2) which terminates in arms 52 and 54 (Fig. 3) and is joined to an upright portion having 20 a pointed end 56 (Fig. 4). The upright portion of the presser foot is provided with a rearwardly extending stud 58 (Figs. 4 and 8) passing through a bushing located in a slot 60 in the lower end of the bracket 40. 25 A spring 62 (Fig. 8) joined to the stud and to a fixed point on the bracket 40 urges the stud 58 upwardly in the slot 60 and pulls the pointed end 56 into engagement with one or the other of two notches 64 formed 30 in a plate 66 (Figs. 2 and 8) attached to the bracket 40. A retaining plate 68 overlaps the pointed end 56 and the notches 64 of the plate 66 to hold the presser foot in engagement with the bracket 40. In the illustrated 35 arrangement, the punching position is illustrated by the dotted lines 70 (Fig. 2) and the line of feed extends vertically of the sheet of drawings through this position, as indicated by the arrow. It will be seen, 40 therefore, that the presser foot mechanism provided is reversible quickly and certainly so that it will occupy two positions, in one of which a toe will contact with the work to the left of the line of feed and in the 45 other of which a toe will contact with the work to the right of the line of feed, as indicated in Figs. 9 and 10 respectively.

The illustrated work-positioning mechanism comprises a reversible edge gage which 50 may be quickly and accurately positioned upon opposite sides of the line of feed and exactly at equal distances away from the line of feed. This gage comprises a gage member 72, the opposite ends of which are 55 rounded and suitable for engagement with the edge of a piece of work. As illustrated the gage member 72 is an integral part of a bar 74 having a vertical flange 76 and adjustably mounted in a groove in a slide 78. 60 The gage member may be moved by means of this adjustment toward and away from the punching position and held in adjusted position by means of a screw 80. This allows the gage to be brought as close as 65 is desired to the particular punch. Pref-

erably the machine is provided with a lever (not shown) by means of which the punch may be moved away from the operator out of the punching position when it is desired to transfer the gage 72 from one position 70 to the other. Preferably, too, a hold-down bar 82 is adjustably associated with the gage and supported thereon by means of a bracket 84 in overlying relation to the edges of the piece of work which is being guided by the 75 opposite rounded ends of the gage member 72. This hold-down bar performs the well-known function of preventing the curling of the edges of the piece of work as it is guided through the machine. In order to make the hold-down bar effective for varying thicknesses of leather, an adjusting screw 86 has a reduced neck which is rotatably secured in a slotted end of the bracket 84 (Figs. 3 and 6) and the screw 86 is threaded into the hold-down bar 82 so that the hold-down bar may be raised or lowered with respect to the gage member upon which the bracket 84 is mounted. It will be seen 80 that the gage member 72 and the flange 76 85 rigidly position the hold-down bar against twisting.

To supplement the mechanism thus far described, I have provided an arrangement by means of which the slide 78 carrying the double-edged gage may be moved from one side to the other of the line of feed in order to bring the opposing edges of the gage 72 into positions exactly equally spaced from the line of feed without loss of time. To this end the slide 78 is guided in a suitable groove 88 (Fig. 3) in the work-supporting table 14 for movement transversely of the table and the table is slotted at 90 (Fig. 2) to allow the passage of a depending 100 pin 92 secured to the slide 78. A hand lever 94 is pivotally mounted beneath the table upon a headed stud 96 and is provided with a slot 98 (Figs. 2 and 7) engaging pin 92. This lever 94 has a finger piece 100 extending beyond the edge of the table, as shown in Figs. 1, 2 and 4, so that it may be easily moved by the operator to change the slide 78 from one position to another. To define the two positions of the slide 78 and hence 105 of the edge gage 72, I have provided an arcuate slot 102 in the hand lever 94, the edges of which are beveled downwardly and outwardly, as shown in Fig. 7, for engagement with the upper pointed end of a rod 104 110 slidably supported for vertical adjustment in a bracket 106 secured to the under side of the work table 14. This arrangement of the parts allows the movement of the edge gage to two alternative positions in each of which its work-engaging surface is exactly the same distance from the punching position and hence from the line of feed. By adjusting the rod 104 vertically, these positions 115 may be varied but will always be equally 120 125 130

4
spaced from the line of feed. To effect such an adjustment the rod 104 is provided with an inclined face 108 which is engaged by the conical end of a horizontal screw 110 threaded in the bracket 106.

In using the above-described machine in accordance with the novel method of this invention to perforate work such as the pointed shoe tip illustrated in Figs. 9 and 10, the 10 presser foot and the edge gage will be relatively positioned with the edge gage at one side of the line of feed, for example at the right of the line of feed, and with the presser foot contacting with the work on the other 15 side of the line of feed, as indicated in Figs. 1, 4 and 9. In the first part of the operation, the perforations beginning at the peak of the tip or at a predetermined distance therefrom, as indicated by the letter 20 A, will proceed from this reference point along one side of the tip, for example to the point B after which the work will be removed from the machine, the presser foot depressed and partially rotated to bring the other foot into engagement with the work, and the edge gage moved to its other position by grasping the finger piece 100 and moving the slide to its other extreme position. The operator then reverses the work 25 and replaces it in the machine with the point A immediately under the punch or so that the next perforation will have the same relation to the peak of the tip that the first perforation has and to this end the machine is preferably arranged so that the punch 30 may be brought slowly down almost into contact with the work, or else the work support may be raised to secure a like result, after which the machine may be started, in 35 order to perforate the other side of the work as indicated by the line A—C. The body of the piece of work will be at one side of the line of feed during one part of the operation and at the other side of the line of feed 40 during the other part of the operation.

Having described my invention, what I claim as new and desire to secure by Letters Patent of the United States is:

1. In a machine of the character described, 50 means for operating upon a piece of work and feeding it along a line, a presser foot for holding the work, said presser foot being constructed and arranged so that it may be shifted into a position to contact with the work at either side of the line of feed, a 55 gage member having opposed edges suitable for contact with the work to guide the same, and means for moving said gage member into corresponding positions upon opposite 60 sides of the line of feed.

2. In a perforating machine, means for 65 perforating a piece of work and feeding it step by step along a line, a presser foot for holding the work intermediate between the 70 feeding steps, means for supporting said

presser foot constructed and arranged to allow it to be shifted to contact with the work on either side of the line of feed, an edge gage having opposed work-contacting surfaces, and means for shifting said gage 75 into positions on opposite sides of the line of feed equally spaced therefrom so that work guided by the opposite edges will receive perforations equally spaced from the edge of the work whether guided by one or 80 the other face of the gage.

3. In a perforating machine, means for punching a piece of work and feeding it step by step along a line, a presser foot for holding the work intermediate of the feeding operations, said presser foot being provided with a pair of feet, means for supporting the presser foot arranged so that either of the feet may be brought into operative relation with the work but upon opposite sides of the line of feed, a two-faced edge gage, means for moving said gage into either of two operative positions so that the perforations will be equally spaced from the edge of the work regardless of which position the edge gage occupies, and means for adjusting said positions.

4. In a machine of the character described, mechanism for retaining a piece of work in position comprising a presser foot bar, a 95 presser foot movably supported on said bar, and means comprising notches and a spring for retaining said presser foot in any one of a plurality of work-retaining positions on the bar, each having a predetermined relation to the line of feed.

5. In a machine of the character described employing mechanism for feeding a piece of work along a line, said mechanism including means for holding the work comprising a 105 presser foot bar, a presser foot movably mounted on said bar, and means for retaining said presser foot in either of two positions constructed and arranged to cause the presser foot to be applied to the work upon 110 opposite sides of the line of feed.

6. In a machine of the character described embodying feeding mechanism, holding mechanism for retaining a piece of work in position intermediate of the feeding operations comprising a reciprocating presser foot bar, a presser foot movably mounted on said bar provided with a pair of toes, and means for retaining said presser foot with either 115 toe in operative relation to the work.

7. In a machine of the character described embodying feeding mechanism to move a piece of work along a line step by step, mechanism for intermittently holding the work between the feeding operations comprising a support, a presser foot having a 125 pair of toes movably mounted on said support, and means for retaining said presser foot in either one of two positions upon the support so that a corresponding toe may be 130

brought into operative relation with the work upon either one side or the other of the line of feed.

8. In a machine of the character described embodying mechanism for feeding a piece of work along a line, means for holding the work in position intermediate of the feeding operations comprising a support, a presser foot with two work-contacting toes pivotally and slidably mounted on said support, said support being provided with notches to receive a part of the presser foot member, said notches being arranged to hold the presser foot in opposed positions so that either one toe or the other is in engagement with the work, and resilient means urging said presser foot member into engagement with a notch.

9. In a machine of the character described embodying mechanism for feeding a piece of work along a line, a gaging device having two gaging surfaces, and means for moving said gaging device to bring the said surfaces alternately into operative relation to the work at equal distances from the line of feed.

10. In a machine of the character described embodying mechanism for feeding a piece of work along a line, a gaging device having opposed work-contacting surfaces, said gaging device being slidably mounted, means for sliding the gage to bring said gaging surfaces alternately into operative relation to the work at equal distances from the line of feed, and a member mounted on the gaging device and arranged to overhang and hold down the edge of the work adjacent to the gage, said member being adjustably supported on the gaging device to coact with varying thicknesses of work.

11. In a machine of the character described embodying mechanism for feeding a piece of work along a line, a gaging device having opposed work-engaging surfaces, a slide supporting said gaging device for movement to bring either of the work-engaging surfaces into operative relation upon opposite sides of the line of feed, and means for moving said slidable support.

12. In a machine of the character described embodying mechanism for feeding a piece of work along a line, a gaging device having opposed work-engaging surfaces, a slide supporting said gaging device for movement to bring either of the work-engaging surfaces into operative relation upon opposite sides of the line of feed, means for moving said slidable support, and adjustable means for limiting the movement of the slide.

13. In a machine of the character described embodying mechanism for feeding a piece of work along a line, a gaging device having opposed work-engaging surfaces, a slide supporting said gaging device for movement to bring either of the work-engaging surfaces into operative relation upon

opposite sides of the line of feed, means for moving said slidable support, and a single means coacting with a movable part constructed and arranged adjustably to limit the movement of the sliding support so that the opposed engaging surfaces will be brought into positions equally spaced from the line of feed.

14. In a machine of the character described embodying means for feeding a piece of work along a line, a work-supporting table, a slide on said table movable in a direction perpendicular to the line of feed, a two-edged gage mounted on said slide, a lever for moving the slide to bring one edge or the other of the gage into operative relation to and upon opposite sides of the line of feed, and adjustable means for limiting the movements of the lever so that the opposed edges of the gage will be brought into positions equally spaced from the line of feed.

15. In a machine of the character described embodying means for feeding a piece of work along a line, a work-supporting table, a slide on said table movable in a direction perpendicular to the line of feed, a two-edged gage mounted on said slide, a lever for moving the slide to bring one edge or the other of the gage into operative relation to and upon opposite sides of the line of feed, and a single means adjustably mounted on the table and arranged to co-operate with said lever to limit its movement so that the opposing edges of the gage may be brought into positions equally spaced from the line of feed.

16. In a machine of the character described, a working tool, means for feeding a piece of work along a line, a work-supporting table, a slide on said table movable in a direction angularly related to the line of feed, a gage on said slide, and means for adjusting said gage with respect to the slide toward and away from the working tool.

17. In a machine of the character described, a working tool, means for feeding a piece of work along a line, a work-supporting table, a slide on said table movable in a direction angularly related to the line of feed, a two-edged gage on said slide, a hold-down mounted on said gage arranged to overlie the edges of the gage, and means for adjusting said hold-down to co-operate with varying thicknesses of work.

18. In a machine of the character described, a working tool, means for feeding a piece of work along a line, a work-supporting table, a slide on said table movably mounted in a direction angularly related to the line of feed, a two-edged gage carried by said slide, a lever pivotally mounted upon the table having a slot, and a pointed member co-operating with said slot to limit movements of the lever equally to space the op-

posed edges of the work gage from the line of feed.

19. In a machine of the character described, a working tool, means for feeding 65
5 a piece of work along a line, a work-supporting table, a slide on said table mounted for movement in a direction angularly related to the line of feed, a two-edged gage carried by said slide, a lever pivotally 70
10 mounted upon the table having a slot, a pointed member co-operating with said slot to limit movements of the lever equally to space the opposed edges of the work gage from the line of feed, and means to adjust 15
16 the pointed member to vary the distances of the edges of the gage from the line of feed.

20. In a machine of the character described, means to feed a piece of work along a line, a work-supporting table, a slide 80
20 mounted on said table for movement in a direction angularly related to the line of feed, a two-edged gage carried by said slide, a lever for moving said slide provided with a slot having downwardly and outwardly 85
25 beveled edges, a pin having a pointed upper end adjustably supported on said table for engagement with the ends of said slot, and means for adjusting said pin.

21. The method of producing angularly 90
30 related intersecting rows of perforations comprising recurrent units which consists in starting with the first unit at or near the desired point of intersection of the rows, producing the first row while moving the work 95
35 to perforate progressively away from the point of intersection, and then starting again at the same corner with a perforation in a predetermined relation to said point and moving the work to perforate progressively 100
40 away from the point to produce a second row of perforations in angular relation to the first row.

22. The method of producing angularly 105
45 related intersecting rows of perforations comprising recurrent units which consists in starting with the first unit in a predetermined relation to the desired point of intersection, producing the first row while moving the work to perforate progressively 110
50 away from the point of intersection, and then starting again at the same point with a perforation in the same predetermined relation to the point of intersection as was the first perforation of the first row and moving 115
55 the work to perforate progressively away from the point to produce a second row of perforations in angular relation to the first row.

23. The method of producing angularly 120
60 related intersecting rows of perforations upon a pointed vamp which consists in starting the perforating operation with the punch

located in a definite relation to the point of intersection, perforating the vamp to produce one row, then again starting the operation at the point of intersection with the punch in a position to register with the first hole of the first row, and moving the work away from said point to produce a second angularly related row of perforations. 70

24. The method of producing angularly related rows of perforations along adjoining edges of a piece of work, which consists in starting the operation with a perforation located in a definite relation to the corner between the adjoining edges, perforating along one side while holding the work against a gage positioned for engagement with the adjacent edge, and then starting again at the same corner and perforating along the other side while holding the work against an edge gage positioned for engagement with the edge adjacent to the last-mentioned side. 75

25. The method of perforating a pointed toe tip which consists in starting the perforating operation with the punch located in a definite relation to the point of the tip, perforating the work along one side of the point while guiding the work by means of a gage positioned in engagement with the adjacent edge, reversing the work, placing it in a position to start the punching operation at the same point with one tool of the punch in a position to register with a hole 95
previously made, and perforating the work along the other edge of the tip while guiding the work by means of an edge gage positioned for engagement with the edge adjacent to the last-mentioned row of perforations. 100

26. The method of producing two rows of perforations along adjacent edges of and meeting at the corner of a piece of work in such a fashion that at least one perforation is common to both rows which consists in commencing at the corner and making one row of perforations by means of recurrent units while guiding the work by means of an edge gage positioned in contact with the adjacent edge of the work, removing the work from the machine, reversing the edge gage, replacing the work in the machine ready to start perforating at the same corner, producing another row of perforations at an angle to the first-mentioned row by means of recurrent units, and guiding the work for this row of perforations by bringing the adjacent edge of the work into contact with the reversed edge gage. 110
115

In testimony whereof I have signed my name to this specification.

FRANK BYCROFT KEALL.
